UNITED STATES PATENT OFFICE.

FRANCIS B. STEVENS, OF NEW YORK, N. Y.

IMPROVEMENT IN VALVES FOR STEAM-ENGINES.

Specification forming part of Letters Patent No. 40,509, dated November 3, 1863.

To all whom it may concern:

Be it known that I, FRANCIS B. STEVENS, of New York, in the county and State of New York, have invented an Improvement in Valves for Steam-Engines, of which the following is a specification.

In a patent for "an improvement in valves for heating the feed-water of steam-engines," granted to me on the 1st day of July, A. D. 1862, and numbered 35,788, a valve is described at Figures VIII and IX, by which the steam can be discharged from the cylinder of a double-eduction steam-engine by the first eduction, providing that this valve communicates with a passage-way made midway in the length of the cylinder; and as the valves discharging the steam by the first eduction may have the pressure alternately in opposite directions, this valve is shown to be retained on its seat by maintaining a constant pressure on its top by steam led from the boiler.

The object of my invention is to improve this valve by dispensing with the action of the steam from the boiler to keep it on its seat, and by substituting instead two seats, so that when there is a plenum in the cylinder the valve may bear against one seat, and when there is a vacuum in the cylinder the valve may bear against the opposite seat, the openings 6, 7, and 8 being placed on one seat and communicating with the opening D placed on the opposite seat.

Fig. I is a full-sized longitudinal section of the valve and the two seats.

A is one seat, and B is the other seat, with its face placed parallel to the face of A.

C is a valve, the throw or motion of which is five inches—the same as in valve referred to. It is not necessary that this valve be so fitted that its two faces shall be in contact with the faces of the seats A and B at the same time, as a small amount of play is admissible. The openings 6, 7, 8, and 9 are the same as in the valve above referred to, but the openings 10 and 11 are omitted in the seat A, and instead the opening D is placed in the

seat B, the width of this opening D being equal to the aggregate width of the openings 6, 7, and 8.

The number of openings in the seat A can be greater or less than shown, but the width of the opening D must equal the aggregate width of the openings in the seat A, and the width of the bridges E F between the openings of the seat A must be a little greater than the opening D. This valve can be simplified by making but one opening in the lower seat, as well as in the upper seat, as in the full-sized longitudinal section shown in Fig. II, where F is the lower seat, G the upper seat, H the valve, and I the opening in the lower seat, made equal in width to one of the openings 6, 7, or 8, and K the opening in the upper seat, the throw being five inches, as in Fig. I. Here, although the time at which the valve commences to open and at which it closes will be the same as in Fig. I, the opening will be only one-third as great as in Fig. I; and if the opening in both seats is made as large as D, and if the time at which the valve commences to open and to close is the same as in Fig. I, then the valve would require a motion or throw of fifteen inches, instead of five inches, because the opening D would be three times the opening of I.

What I claim as my invention is—

1. A slide-valve connected with a passage made midway in the length of a cylinder and made to bear alternately with its opposite faces against two seats, as herein set forth and described.

2. In connection with my first claim, placing a greater number of openings in one seat than in the other, as a means of diminishing the throw of the valve without decreasing the size of the passage-way, as herein set forth and described.

Dated June 8, 1863.

FRANCIS B. STEVENS.
